UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed January 19, 1931. Serial No. 509,640.

This invention relates principally to car roofs of the flexible single-course type where-in the roof sheets are secured to each other and to the car by seam caps that permit movement of said roof sheets to a limited extent so as to be able to accommodate themselves to the distortions of the car body. Its principal objects are to prevent leakage between the roof sheets and the seam caps, to provide for supporting the marginal portions of adjacent sheets on the carlines and to dispense with the use of purlins for supporting the roof sheets between carlines. The invention consists in the car roof and in the construction, combinations and arrangements of parts hereinafter described and claimed.

In the accompanying drawings, which form part of this specification and wherein like symbols refer to like parts wherever they occur,

Fig. 1 is a plan view of a car roof embodying my invention,

Fig. 2 is a vertical transverse section through said roof on the line 2—2 in Fig. 1, Fig. 3 is an enlarged fragmentary plan view of the eaves portion of the car in the region of one of the roof seams,

Fig. 4 is a vertical transverse section through the eaves portion of the roof on the line 4—4 in Fig. 1,

Fig. 5 is a fragmentary side elevation of the roof, showing the eaves end of one of the seam caps,

Fig. 6 is a vertical section on the line 6—6 in Fig. 4,

Fig. 7 is a similar section on the line 7—7 in Fig. 4; and

Fig. 8 is a similar section on the line 8—8 in Fig. 4.

The present construction comprises side plates A of substantially Z-shaped cross-section with the inner flange 1 upstanding and having riveted flatwise against the outer side of said flange an angle-shaped member B whose upper leg 2 extends inwardly over the top of said side plate at an angle conforming to the pitch of the roof and at the proper elevation for the end portions of metal roof sheets C to rest upon. At suitable intervals, the eaves angle support B has depressions 3

in its top flanges 2 of the proper shape to receive and form seats for the ends of metal carlines D, which are riveted thereto.

The carlines D are made of two members each. The upper or main member 4 of each carline D is in the form of an inverted channel with outstanding base flanges 5 at the lower edges of its side walls, the channel extending from end to end of said upper carline member, but being of reduced depth at the end portions thereof. The upper portion of the channel-shaped body of the upper carline member 4 is made narrower than the lower portion thereof to form exterior sheet supporting shoulders or ledges 6 that extend longitudinally of said upper carline member on opposite sides of the narrow upper portion thereof. The lower carline member 7 is in the form of a plate that extends the full length of the carline and is riveted to the outstanding base flanges 5 of the inverted channel-shaped upper carline member 4. The bottom carline member 7 is made wider than the upper carline member 4 and has its side marginal portions struck up beyond the base flanges 5 of said upper carline member into the form of raised flanges 8 that are of proper height for body portions of the roof sheets C to rest upon.

The roof sheets C extend from eaves to eaves of the car between carlines D and are supported at their eaves ends on the inwardly extending flanges 2 of the combined carline and roof sheet supports B and along their side margins on the ledges 6 of the upper carline members 4 and on the sheet supporting flanges 8 of the lower carline members 7. The side marginal portions of the roof sheets beyond the sheet supporting flanges 8 of the lower carline members 7 are pressed up into raised panels 9 that incline upwardly and outwardly and terminate in vertical flanges 10 at the side edges of said sheets. The side marginal panels 9 of the roof sheets rest upon the longitudinal ledges 6 of the upper carline members 4, which ledges slope downwardly and outwardly at an angle conforming to the slope of said side marginal panels of the roof sheets. The adjacent side flanges 10 of adjacent roof sheets lie on opposite sides of

the narrow upper portion of the inverted channel-shaped upper carline member 4 at a sufficient distance therefrom to afford adequate clearance to provide for distortions of 5 the substructure.

Above the upper member 4 of each carline D and rigidly secured thereto is a transverse seam or carline cap 11 of inverted channel-shaped cross-section with outstanding base flanges 12 that are inclined conformably to 10 the inclination of the inclined side marginal panels 9 of the roof sheets and the inclined sheet supporting ledges 6 of said upper carline member. The inclined side marginal panels 15 9 of the roof sheets and the inclined base flanges 12 of the seam cap 11 are in contact, and the vertical portions of said seam cap are spaced away from the upstanding side marginal seam flanges 10 of the roof sheets 29 far enough to provide for proper clearance. At the ridge of the car the transverse seam caps 11 are rigidly secured flatwise to the tops of the carlines by rivets 13, which also serve to secure running board saddles 14 to 25 the tops of the seam caps, said running board saddles, in turn, constituting supports for a running board 15 which extends longitudinally of the car from end to end thereof.

The eaves end portions of the seam caps 11 30 are removably secured to the reduced end portions of the upper carline members 4 preferably by means of bolts 16 that extend through registering holes provided therefor in the upper and lower carline members and 35 are provided below the lower carline members with nuts 17. The upper or headed ends of the bolts 16 are supported in channel-shaped brackets 18, which are located within the seam caps crosswise thereof and have outstanding flanges 19 at the upper ends of 40 their side walls that are riveted or otherwise permanently secured to the undersides of the top webs of said seam caps. The webs of the channel-shaped bolt supporting brackets 18 45 are provided with notches 20 whereby the bolts may be readily attached to said brackets. The bolt hole 21 in the lower carline member 7 has its edge 21a flanged or winged up to prevent any water that may reach the top 50 of said lower member from passing through said hole. Any water that gets under the roof sheets onto the lower carline members 7 will drain lengthwise thereof and be delivered over the ends of the carline to the outside of the car.

In order to render the roof sheets strong enough to transmit the vertical roof load from the roof sheets to carlines, the unsupported middle portions of said sheets are provided 55 with upstanding corrugations or stiffening ribs 22 that span the spaces between the sheet supporting flanges 8 of adjacent carlines and overlap said flanges. By thus strengthening the roof sheets, the use of purlins is dispensed with, thereby saving the cost of the purlins

and relieving the carline of the weight thereof.

The roof sheets are provided at their eaves ends with depending flanges 23 that overhang and are spaced from the combined carline and roof sheet supports B and the upstanding side plate flanges 1 to which said supports are secured; and likewise, the eaves ends of the transverse seam caps 11 are provided with depending flanges 24 that overhang and are spaced from adjacent end portions of depending eaves flanges 23 of adjacent roof sheets. The eaves flanges 23 of the roof sheets terminate at their lower ends in 70 inwardly extending horizontal flanges 23a that are spaced from the supports B and likewise, the depending end flanges 24 of the seam caps terminate in inwardly extending horizontal flanges 24a that bear flatwise 75 against the undersurfaces of the adjacent end portions of the inturned lower ends 23a of the depending eaves flanges 23 of adjacent roof sheets and are also spaced from the supports B. By this arrangement, the eaves ends of the seam caps are hooked beneath the 80 eaves ends of the roof sheets and serve to hold the base flanges 12 of said caps and the raised side marginal panels 9 of said roof sheets in contact with each other from the securing bolts 16 out to the eaves. In order 85 to stiffen the seam caps where they are turned down to form the depending end flanges 24 and where said flanges are turned inwardly to form the flanges 24a, the caps are pressed 90 inwardly to form strengthening corrugations 95 100 25 and 26, respectively.

By the arrangement just described, when the car goes out of square under service conditions, the roof sheets slue or oscillate about their centers; and as an incident to this movement, two diagonally opposite corners of a sheet move away from the adjacent side plates respectively while the other two diagonally opposite corners of said sheet move toward said side plates respectively, producing at the eaves what is commonly known as a saw-tooth effect. This movement of the two diagonally opposite corners of the sheet away from the side plate causes the rebent lower end portions 23a of the depending eaves flanges 23 of said sheet to lower and thus 105 press downwardly upon the rebent lower ends 24a of the depending end flanges of the seam caps and force the latter down upon the roof sheets; and this downward pull on the seam caps throws a twist in the sheet and causes the other two diagonally opposite corners of the sheet to spring upwardly into engagement with the underside of the seam cap. 110

By the arrangement described, the raised side marginal panels 9 of the roof sheets are supported throughout their length on the ledges 6 of the carlines and are thus prevented from falling away from the base flanges 12 of the transverse seam caps, which flanges, 115 120 125 130

in turn, are held down upon said raised side marginal panels by the rivets 13, which secure the running board saddles 14 in place, by the bolts 16 adjacent to the eaves and by the inturned flanges 24a at the lower ends of the depending end flanges 24 of said seam caps. The roof sheets are further supported adjacent to the inner edges of their raised side marginal panels 9 by the upward-
ly offset sheet supporting flanges 8 of the lower carline members 7, while the corrugations or ribs 22 formed in said roof sheets span the spaces between the sheet supporting flanges 8 of adjacent carlines and thus serve to increase the vertical strength of the unsupported middle portions of said roof sheets and render them strong enough to support the vertical roof load. The bolts 16 for securing the eaves portions of the seam caps to the carlines are supported in the brackets 18 that are permanently attached to the seam caps and are slotted to permit said bolts to be readily attached to and detached from said brackets when the caps are detached from the car; and the pressure of said caps on the roof sheets may be regulated by tightening or loosening the nuts 17 on the lower end of said securing bolts.

Obviously, the hereinbefore described construction admits of considerable modification without departing from the invention. Therefore, I do not wish to be limited to the precise arrangements shown and described.

What I claim is:

- 35 1. A car roof comprising side plates, carlines supported by said side plates and roof sheets movably supported on said side plates and carlines, said carlines having their side margins raised to provide supports for said roof sheets, said roof sheets being provided with stiffening ribs that extend from the roof sheet support of one carline to the roof sheet support of the adjacent carline.
- 40 2. A car roof comprising side plates, carlines supported by said side plates and roof sheets movably supported on said side plates and said carlines, a carline comprising an upper member of inverted channel-shape with the upper portions of its side walls offset inwardly to form longitudinal supporting ledges for the side marginal portions of adjacent roof sheets, and a lower plate-like member secured to the bottom of said upper carline member, said lower member being wider than said upper member and having its side margins raised beyond said upper member to form supports for said roof sheets outwardly beyond and somewhat lower than said ledges.
- 45 3. A car roof construction comprising side plates, carlines supported by said side plates, roof sheets movably supported on said side plates and said carlines, a carline comprising an upper member of inverted channel-shape with the upper portions of its side walls offset inwardly to form supports for the inclined side marginal panels of said sheets that are inclined conformably to the inclination thereof, and a lower plate-like member secured to the bottom of said upper carline member, said lower member being wider than said upper member and having its side margins raised beyond said upper member to form supports for the portions of said roof sheets that are located inside their side marginal panels.
- 50 4. A car roof comprising side plates, carlines supported by said side plates and roof sheets movably supported on said side plates and carlines, said roof sheets having their side margins formed into panels that are raised above the bodies of the roof sheets, said carlines having their side margins raised to provide supports for the bodies of said roof sheets and being provided intermediate said raised side margins with longitudinal ledges slightly higher than said supports for supporting the side marginal panels of said roof sheets.
- 55 5. A car roof comprising side plates, carlines supported by said side plates and roof sheets movably supported on said side plates and carlines, said roof sheets having their side margins formed into panels that are raised above the bodies of the roof sheets, said carlines having their side margins raised to provide supports for the bodies of said roof sheets and being provided intermediate said raised side margins with longitudinal ledges for supporting the side marginal panels of said roof sheets, the body portions of said roof sheets being provided with stiffening ribs that extend from the raised side marginal roof sheet support of one carline to the raised side marginal roof sheet support of an adjacent carline.
- 60 6. A car roof construction comprising side plates, carlines supported by said side plates, and roof sheets movably supported on said side plates and said carlines and having their side margins pressed into raised panels that incline upwardly and outwardly, a carline comprising an upper member of inverted channel-shape with the upper portions of its side walls offset inwardly to form supports for the inclined side marginal panels of said sheets that are inclined conformably to the inclination thereof, and a lower plate-like member secured to the bottom of said upper carline member, said lower member being wider than said upper member and having its side margins raised beyond said upper member to form supports for the portions of said roof sheets that are located inside their side marginal panels.
- 65 7. A car roof having a substructure including side plates, roof sheets movably supported on said side plates, and seam caps straddling the side marginal portions of adjacent roof

sheets and secured to said substructure intermediate said side plates, said roof sheets being provided with depending eaves flanges that overhang and are spaced from said side plates, said seam caps having depending end flanges that overhang and are spaced from the depending eaves flanges of adjacent roof sheets and are provided at their lower ends with inwardly extending flanges that bear against the lower ends of said depending eaves flanges.

8. A car roof comprising side plates, carlines supported by said side plates, roof sheets movably supported on said side plates and said carlines, and seam caps straddling said carlines and the side marginal portions of adjacent sheets and secured to said carlines intermediate said side plates, said roof sheets being provided with depending eaves flanges that overhang and are spaced from said side plates, said seam caps having depending end flanges that overhang and are spaced from the depending eaves flanges of adjacent sheets and are bent inwardly beneath and in contact with the lower ends of the depending eaves flanges of adjacent roof sheets.

9. A car roof comprising side plates, carlines supported by said side plates, roof sheets movably supported on said side plates and said carlines, seam caps secured to said carlines intermediate said side plates and straddling said carlines and the side marginal portions of adjacent sheets, said seam caps having base flanges resting upon adjacent roof sheets, said roof sheets being provided with depending eaves flanges that overhang and are spaced from said side plates and are bent inwardly at their lower ends, said seam caps having depending end flanges that overhang and are spaced from the depending eaves flanges of adjacent sheets are provided at their lower ends with inwardly extending flanges that bear against the undersides of the inwardly bent lower ends of the depending eaves flanges of adjacent roof sheets.

10. A car roof comprising side plates, carlines supported by said side plates, roof sheets movably supported on said side plates and said carlines, seam caps secured to said carlines intermediate said side plates and straddling said carlines and the side marginal portions of adjacent sheets, said seam caps having base flanges resting upon adjacent roof sheets, said roof sheets being provided with depending eaves flanges that overhang and are spaced from said side plates and are bent inwardly at their lower ends, said seam caps having depending end flanges that overhang and are spaced from the depending eaves flanges of adjacent sheets are provided at their lower ends with inwardly extending flanges that bear against the undersides of the inwardly bent lower ends of the depending eaves flanges of adjacent roof sheets, said seam caps being provided with a stiffening

corrugation at the angle formed by the top of the caps and their depending end flanges and at the angle formed by the depending end flanges of said caps and the inwardly extending flanges at the lower ends of depending cap flanges.

Signed at New Kensington, Pennsylvania, this 14th day of January, 1931.

CHARLES DAVID BONSALL.
